UNITED STATES PATENT OFFICE.

CHARLES H. WORTHEN, OF LAWRENCE, MASSACHUSETTS.

OIL-CAN.

SPECIFICATION forming part of Letters Patent No. 325,642, dated September 1, 1885.

Application filed June 5, 1885. (No model.)

To all whom it may concern:

Be it known that I, CHARLES H. WORTHEN, of Lawrence, in the county of Essex and State of Massachusetts, a citizen of the United States, have invented a new and useful Improvement in Oil-Cans, of which the following is a full, clear, and exact description, reference being had to the accompanying drawings, forming a part of this specification, in explaining its nature, in which—

Figure 1 is an elevation of a can or oiler having my invention, and Fig. 2 a vertical central section thereof; and Figs. 3 and 4 are details.

15 The object of the invention is to provide an oil-can or oiler having a device by which limited quantities only of the lubricant are expelled with greater or less force, so that, if desired, it can be thrown some distance from the nozzle or with considerable force into an oil-supply passage, or can be pushed gently therefrom and in a small stream, but continuously, until a large quantity has been fed.

25 In the drawings, A represents the body of the cup; B, the nozzle; C, a sleeve which extends from the base of the opening of the nozzle downward into the body of the cup. This sleeve has ports or openings c, and there is arranged within it a movable sleeve, D. There 30 is also arranged to move in this inner sleeve a piston, E, which is operated by the stem or rod e, which extends downward therefrom through a packing-box, F, and through the under surface or bottom of the cup. This piston is so snugly fitted to the sleeve D (leather cup-packing may be used, if desired) that the sleeve is moved upon the movement of the piston until it comes in contact with the inner end of the nozzle-sleeve.

40 The operation of the device is substantially as follows: The piston and moving sleeve being at their lowest position in the cylindrical casing, to discharge the contents of the cup the piston is moved forward toward the nozzle. This also moves the sliding sleeve, and the movement is continued until the upper edge of the sliding sleeve comes in contact with the shoulder or stop c', when it is stopped and the ports or openings c closed. The movement of 45 the piston, however, is still continued, thereby

expelling all the oil or lubricant that is contained in the sleeve into the nozzle. Upon the backward movement of the piston the sleeve is moved with it and the openings or ports c uncovered, thereby allowing the piston to draw 55 into the chamber of the sleeve and casing a supply of oil, and the reverse movement of the sleeve is continued until it strikes the rear shoulder or stop, c', when it comes to rest, and the reverse movement of the piston is continued to until it reaches the end of its reverse throw.

The outer casing or sleeve, C, is open at its lower end. It will thus be seen that the quantity of oil or other lubricant is measured and then forced from the measuring-chamber by 65 the movement of the piston with greater or less force and to a greater or less distance from the end of can, according to the speed of the movement of the piston.

The packing-box is constructed by forming a hole at the bottom of the cup and attaching to the bottom a sleeve, G, through which the stem e passes, and in which any suitable packing may be confined by means of the plate or disk f, which is attached by solder to the 75 sleeve, leaving a sufficient space, f', below, if desired, for the reception of the ring or cap at the end of the piston-spindle.

The nozzle of the oiler preferably is fastened to the cup by what is sometimes known as a 80 "bayonet-joint"—that is, by means of pins or projections b, extending outward from the nozzle-butt, and bayonet-slots b', formed in the neck of the can or sleeve C. The lower end of the nozzle is adapted to enter the upper end 85 of the casing, so that when in position its lower edge acts as a stop to the sliding sleeve.

It will be observed that this construction is 90 cheap and simple and efficient, and that for medium and large-sized oilers it is very desirable, because it prevents waste, as it is obvious that the cup may be held in any position in oiling, and yet only the quantity which is contained in the cylinder can escape.

Having thus fully described my invention, I 95 claim and desire to secure by Letters Patent of the United States—

1. An oil-can or oiler having the sleeve or casing C, opening into a discharge-passage, and having one or more ports, c, with the sleeve . . .

D, movable therein, and the piston E, movable in said sleeve, all substantially as and for the purposes described.

2. The combination, in an oiler, of the body A, the casing or cylinder C, having one or more openings or ports, c, the sleeve D, movable in said cylinder or casing, and the piston E, movable in said sleeve, and stops for controlling the movements of the sleeve, all substantially as and for the purposes described.

3. The combination, in an oil-cup or oiler, of the nozzle B, the casing or cylinder C, arranged in relation to the nozzle as shown, and having ports c, with the sleeve D and piston E, all substantially as and for the purposes described.

CHARLES H. WORTHEN.
